VEHICLE FUEL TANK

Michael R. Graeper, 2 Britten Court,
Lake Oswego, Oreg. 97034

Filed June 27, 1974, Ser. No. 483,797

Term of patent 14 years

Int. Cl. D12—16; D23—01
U.S. Cl. D12—155

FIG. 1 is a top perspective view of a vehicle fuel tank showing my new design; and

FIG. 2 is a bottom perspective view thereof showing the side and end opposite to those shown in FIG. 1.

I claim:

The ornamental design for a vehicle fuel tank, as shown.
